(57) **CLAIM**

The ornamental design for a sleeve end for an athletic performance shirt with wrist device opening, as shown and described.

DESCRIPTION

FIG. 1 is a top perspective view of an end portion of a sleeve for an athletic performance shirt illustrating a thumb opening and an opening for a wrist device; and,

FIG. 2 is a bottom perspective view of the end portion of the sleeve illustrated in FIG. 1 showing a cover that is positionable over the opening for the wrist device.

The broken line showing of a wrist device is for the purpose of illustrating environmental structure and forms no part of the claimed design.

The broken lines illustrating stitching on the garment represent portions of the article that form no part of the claimed design.

The dot-dash broken line illustrates the boundary of the claim and forms no part of the claimed design.
